UNITED STATES PATENT OFFICE.

MARTIN NEWCOMER, OF NEW YORK, N. Y., ASSIGNOR TO VOLOTONE COMPANY, OF ELIZABETH, NEW JERSEY, A CORPORATION OF NEW JERSEY.

PNEUMATIC DEVICE FOR MUSICAL INSTRUMENTS.

1,130,101.

Specification of Letters Patent.

Patented Mar. 2, 1915.

Application filed January 31, 1911. Serial No. 605,836.

To all whom it may concern:

Be it known that I, MARTIN NEWCOMER, a citizen of the United States, residing in the borough of Manhattan of the city of New York, in the State of New York, have invented certain new and useful Improvements 5 in Pneumatic Devices for Musical Instruments, &c., of which the following is a specification, reference being had to the accompanying drawings, forming a part hereof.

It is well known, especially to those who are expert in the manufacture and in the use of pneumatic piano players and the like, that the sluggishness of the return movement of 15 the movable member of a pneumatic device or bellows, such as a striking pneumatic or a sustaining pedal pneumatic or any other pneumatic or bellows by which some part of the instrument is actuated, is a serious 20 obstacle to the thoroughly artistic rendition of a musical composition. Various means have been devised hitherto for the purpose of overcoming this difficulty but thus far they have failed to overcome the difficulty in a 25 satisfactory manner but have introduced or magnified other difficulties.

It is the object of this invention to provide means whereby the movable member of such a pneumatic device or bellows shall be 30 permitted to respond instantly and freely to the spring or other force by which the movement thereof is effected as soon as the pressure conditions within such device or bellows are changed in character, as by the 35 breaking of the vacuum. In accordance with the invention such a pneumatic device or bellows is provided with an auxiliary port through which the interior of the device or bellows may be placed in direct 40 communication with the atmosphere and with a valve to control such port which closes the port while the device or bellows is subject to the actuating pressure and is moved by mechanical means to open the 45 port, so as to establish free communication between the interior and the atmosphere as soon as the return movement of the movable member commences, so that the continuation of such return movement is free and unimpeded.

The invention will be more fully explained hereinafter with reference to the accompanying drawings in which it is illustrated and in which—

Figure 1 is a view partly in elevation and

partly in section illustrating the application of the invention to the pneumatic device or bellows which controls the hammer rest rail. Fig. 2 is a view of the pneumatic device or bellows as seen from the left-hand in Fig. 1, 60 the bellows being collapsed. Fig. 3 is a view similar to Fig. 2 but showing the bellows expanded. Fig. 4 is a top view of the bellows. Fig. 5 is a view generally similar to Fig. 3 but showing a different embodiment of the 65 invention. Fig. 6 is a top view of the bellows shown in Fig. 5. Figs. 7 and 8 are front, end views showing still another embodiment of the invention, with the bellows collapsed in Fig. 7 and expanded in Fig. 8. 70 Fig. 9 is a top view of the bellows shown in Figs. 7 and 8. Fig. 10 is a view similar to Fig. 1 but showing also the connection of the bellows to the wind chest and the controlling devices.

Referring first to the embodiment of the invention shown in Figs. 1, 2, 3, 4, and 10 in which the invention is illustrated as applied to the pneumatic device or bellows *a* which, through the rod *b*, controls the position of the movable rest rail *c* for determining the throw of the hammers *d*, it will be seen that the pneumatic device or bellows *a* is of ordinary construction, comprising a relatively fixed member *e* and a relatively 85 movable member *f*. A spring *g* is applied to the bellows for effecting expansion of the bellows or the return movement of the movable member *f* and a connection *h* to the wind chest or power bellows is provided in the usual manner. As shown in Fig. 10 the port *h* may be connected to a wind chest *r* or to the atmosphere through a double valve *s* which is actuated by a diaphragm *t* in the wind chest, while the 90 chamber *t'* below the diaphragm is connected by a tube *t''* with a port *t'''* controlled by a finger valve *v*. When the valve *v* is open, as shown, atmospheric pressure is admitted to the underside of the diaphragm *t* and the 95 double valve *s* is then moved to the position shown so that the interior of the bellows *a* is then connected with the atmosphere and the bellows is expanded by the spring *g*. More or less resistance is offered to the filling of the bellows *a* through the connections to the port *h* and expanding of the bellows is therefore somewhat sluggish, so that the part actuated by the bellows does not respond as quickly as is desirable. It will 100 105 110

be understood, of course, that when the finger valve v is closed and the pressures above and below the diaphragm t are equalized through the usual bleed port, the double valve s moves so as to cut off direct communication with the atmosphere and to establish communication between the interior of the bellows a and the wind chest r for the purpose of collapsing the bellows in the usual way. During the collapsing of the bellows air moves from the bellows outwardly through the port h , but during the expanding of the bellows air moves inwardly through the port h into the bellows. In addition to the usual port or connection h , through which the air is exhausted from the bellows, and through which air also enters the bellows when the valve s is open to the atmosphere, being then drawn in by the expanding movement of the bellows under the influence of the spring g , there is provided an auxiliary port i , indicated by dotted lines in Figs. 2, 3 and 4, through which direct communication may be established between the interior of the bellows and the atmosphere, so that when this port is open the movable member of the bellows will respond instantly and freely to the spring g or other actuating force, and so that when the port is closed the bellows will be subject to the action of the power bellows as determined by the operation of any intermediate valves which may be employed. During the expanding movement of the bellows, as already pointed out, more or less air enters the bellows through the port h and direct communication is then established with the atmosphere through the port i so that the port i is then auxiliary to the port h . The port i is controlled by a valve k , which is held to its seat by atmospheric pressure so long as the vacuum is maintained within the bellows and is moved from its seat to open the port by mechanical means as soon as the vacuum is broken and the movable member f begins its movement, so that the atmospheric air is immediately given free access to the interior of the bellows and the continued movement of the movable member is free and unimpeded. This movement of the valve from its seat is effected by mechanical means in the construction shown in the figures referred to through the relative movement of the two members of the bellows. Thus, in the construction shown, the valve k is carried by a lever k' which is pivoted at k^2 on that member of the bellows in which the port i is formed and to the other members of the bellows is secured an arm l against which the end k^3 of the lever k' has a frictional bearing. In the construction shown an adjustable stop m is supported by an extension l' of the arm l so that as the movable member of the bellows approaches the limit of its return movement the valve k

is pressed toward the port i to close the same and thereby place the bellows in condition immediately for further action under the influence of the vacuum. The arm l may be provided with a screw l^2 by which the arm l may be adjusted as required. It will now be understood that when the bellows has been fully collapsed, with the valve k seated on the port i , as shown in Fig. 2, and air is then admitted to the bellows through the port h , the expanding movement of the bellows, under the influence of the spring g , begins, effecting relative movement of one member of the bellows with respect to the other. The end k^3 of the lever k' has a frictional bearing against the arm l , so that as soon as such relative movement begins, the valve k is moved from the port i , thereby establishing direct communication between the interior of the bellows and the atmosphere and permitting the bellows to expand quickly. As the movable member f approaches the limit of its movement the lever k' strikes the adjustable stop m and the valve k is thereby held so that the movable member f moves against it and effects the closing of the port i . The lever k and the arm l , being in frictional contact, therefore constitute one form of mechanical means by which the auxiliary port i is opened as soon as the vacuum in the bellows is broken by the admission of air through the port h .

In the construction shown in Figs. 5 and 6 the bellows a is constructed substantially as already described, the movable member f having formed therein an auxiliary port i which is controlled by a valve k carried by a lever k' pivoted at k^2 . The short arm k^3 of the lever k' instead of being actuated by the relative movement of the two members of the bellows is acted upon by an adjustable spring n , which may be connected to that member of the bellows upon which the lever k' is mounted. This spring n is so adjusted that its force is sufficient to move the valve k from its seat as soon as the vacuum within the bellows is broken but is insufficient to move the valve from its seat against atmospheric pressure. An adjustable stop m supported, for example, by an arm l' , as before, is provided to close the valve k as the movable member of the bellows approaches the limit of its expanding or return movement.

In the embodiment of the invention shown in Figs. 7, 8 and 9 provision is made not only for the immediate opening of the valve when the vacuum within the bellows is broken and the movable member begins its movement but for the closing or partial closing of the valve during the latter portion of the expanding movement of the bellows, so that such expanding movement may then be retarded as is sometimes desirable.

In this construction the valve k is carried by a lever k' , the short arm k^3 of which co-operates with an arm l as in the construction shown in Figs. 1 to 4. In this case, 5 however, there is also provided another arm o for co-operation with the other end or long arm of the lever k' , such arm o having an offset o' so that the arm shall not co-operate with the lever k' until the bellows has 10 expanded to a predetermined point. At such point, the inset portion of the arm o begins to co-operate with the lever and causes it to close. In this construction, the two arms l and o are spring arms and are adjustably 15 connected by a rod p to which may be connected any suitable controlling devices, as indicated by the bell crank lever q , so that the position of the arms l and o may be controlled by the performer to determine their 20 action.

Various other embodiments of the invention will suggest themselves in view of the foregoing and it is therefore to be understood that the invention is not limited to the 25 precise constructions shown and described herein.

I claim as my invention:

1. The combination with a bellows, provided with a port for connection to the wind chest or the atmosphere and with an auxiliary port through which direct communication may be established between the interior of the bellows and the atmosphere, 30 of a valve to control said auxiliary port, said valve being held normally to its seat by air pressure, a lever supporting said 35

valve and mounted on that member of the bellows in which the auxiliary port is formed, a friction arm secured to the other member of the bellows and co-operating with one arm of said lever, and a second friction arm also mounted on said other member of the bellows to co-operate with the other arm of said lever and having an offset. 40

2. The combination with a bellows, provided with a port for connection to the wind chest or the atmosphere and with an auxiliary port through which direct communication may be established between the interior of the bellows and the atmosphere, 45 of a valve to control said auxiliary port, said valve being held normally to its seat by air pressure, a lever supporting said valve and mounted on that member of the bellows in which the auxiliary port is 50 formed, a friction arm secured to the other member of the bellows and co-operating with one arm of said lever, a second friction arm mounted on said other member of the bellows to co-operate with the other arm of 55 said lever and having an offset intermediate its ends whereby it co-operates with said other arm during a portion only of the relative movement of the lever, and means to control the positions of said friction arms. 60

This specification signed and witnessed this 25th day of January A. D., 1911.

MARTIN NEWCOMER.
